CHARLES M. GILBERT.

Improvement in Bedstead-Fastenings.

U. S. PATENT OFFICE

Patented May 14, 1872.

Fig. 1. *Fig. 1. Areal map of total biomass (kg/ha) and distribution of NPP in the primary forest along the transects.*

Fig. 1.

A diagram is centered on a page filled with dense, illegible text. The diagram consists of a thick black rectangular frame. Inside this frame is a smaller, irregularly shaped oval. Within the oval, there is a smaller circle. A diagonal line is drawn through this circle, creating a 45-degree angle. The entire diagram is set against a background of dense, illegible text.

UNITED STATES PATENT OFFICE.

CHARLES M. GILBERT, OF PHILADELPHIA, PENNSYLVANIA.

IMPROVEMENT IN BEDSTEAD-FASTENINGS.

Specification forming part of Letters Patent No. 126,630, dated May 14, 1872.

I, CHARLES M. GILBERT, of the city and county of Philadelphia, in the State of Pennsylvania, have invented a certain Improvement in Bedstead-Fastenings, of which the following is a specification:

The object of my invention is to make a bedstead-fastening, which, with great simplicity and cheapness of construction, shall unite ease of adjustment and great durability; which shall also make a perfectly-close joint between the bed-post and rail, and which shall not be liable either to work loose with age or grow so tight as to make it difficult to take the bedstead apart.

The references are to the drawing.

Figure 1 is a perspective view of the rail and screw. Fig. 2 is a sectional view of the two screws in place. Fig. 3 is a sectional view of the post with the tubular screw.

The parts of my invention are, a bed-screw of the ordinary form and size; a tubular nut

whose interior face is a female screw, and whose exterior a male screw. The tubular nut is first screwed permanently into the post C, and the screw A is adjusted into the rail as shown in D, which is prepared with a projection against which the screw-head bears.

A is the bed-screw; B, the tubular nut; C, side view of the post with A screwed into position; D, side view of the rail, with B ready for adjustment. *a a* are pins which fit into the holes *b b* to prevent the rail turning from its upright position.

I claim—

The tubular nut B with screw on the outside surface, in combination with the male or bed-screw A, with rail D, pins *a a*, and post C, as shown, for the purpose specified.

CHAS. M. GILBERT.
